UNITED STATES PATENT OFFICE.

CHARLES R. FLEMING, OF HOBERG, MISSOURI, ASSIGNOR OF ONE-THIRD TO OSCAR J. DOSS, OF HOBERG, MISSOURI.

PIANO-VIOLIN.

1,344,497.

Specification of Letters Patent. Patented June 22, 1920.

Application filed November 5, 1915, Serial No. 59,798. Renewed January 15, 1920. Serial No. 351,561.

To all whom it may concern:

Be it known that I, CHARLES R. FLEMING, citizen of United States, residing at Hoberg, in the county of Lawrence and State of 5 Missouri, have invented certain new and useful Improvements in Piano-Violins, of which the following is a specification.

This invention relates to mechanisms for operating upon stringed instruments to produce musical tones, and has for its primary object to generally simplify and improve devices of the type set forth.

A further object of the invention is to provide a device of the character set forth which 15 embodies a plurality of stringed instruments which may be of various sizes, shapes, and types, associated with each of which is a rotatable bow member for contact with the strings thereof and which embodies improved means for selectively actuating the various bow members to produce with their respective strings musical sound and chords.

A further object is to so arrange the operating mechanism of the instruments that 25 the strings of both instruments may be selectively fingered and bowed to sound chords and other combinations of musical sounds.

Another object resides in the particular 30 mechanism for operating the fingering arms and the bowing mechanisms.

In the drawings annexed hereto and forming a part of the invention which I have found in practice to give good results:

35 Fig. 1 is a front elevation of the device with the cover open, and with parts of the mechanism removed.

Fig. 2 is a sectional view on the line 2—2 of Fig. 1.

40 Fig. 3 is a rear elevation.

Fig. 4 is a bottom plan view.

Fig. 5 is a sectional view on the line 5—5 of Fig. 2.

45 Fig. 6 is a sectional view on the line 6—6 of Fig. 5.

Fig. 7 is a sectional view on the line 7—7 of Fig. 1.

Fig. 8 is a sectional view on the line 8—8 of Fig. 1.

50 Fig. 9 is a sectional view on the line 9—9 of Fig. 1.

Fig. 10 is a sectional view on the line 10—10 of Fig. 1.

55 Fig. 11 is a view, in perspective, of the means for adjusting the treadle cables.

Fig. 12 is a sectional view on the line 12—12 of Fig. 11, and,

Fig. 13 is a sectional view on the line 13—13 of Fig. 2.

Fig. 14 is a detailed perspective view of 60 the bow wheel and its associated parts.

The mechanism comprises a case A consisting of the back 1, base 2, sides 3 and cover 4 hinged at 5. On the back 1 are clamps 6 which engage the body of a cello 65 B and hold the same in a suitable vertical position. A second violin C is similarly held by clamps 7.

On one side 3, of the case A, is mounted a pedestal 8 indicated in dotted lines in 70 Fig. 1 and which carries an electric motor illustrated in Fig. 2. Through the medium of a belt 6^a this motor drives a pulley 9 on a short shaft 10 journaled in bearings 11, said bearings being carried by uprights 12 75 mounted on base 2.

The shaft 10 also carries a pulley 13 of smaller diameter which, by means of a belt 14, drives a larger pulley 15 on a jack shaft 16, said jack shaft being mounted in bearings 17 carried by the back 1 of the case A. The jack shaft 16 carries, at one end, a pulley 18 which by means of a belt 19 drives a pulley 20 on a shaft 21 journaled in bearings 22 and 23 supported on one side 3 of 85 case A and the bearing 24 carried by the bracket 25 on back 1. The shaft 21 has fixed thereto a bevel gear 26 which meshes with a similar bevel gear 27 carried by the vertical shaft 28 carrying a bevel disk bow 90 wheel 29 of felt or similar material. The shaft 28 is journaled in bushing 30 carried by an arm 31 which has an extension 32 engaging one end of an angularly disposed arm projecting forwardly from the upper 95 extremity of one arm of the bell-crank lever 33; the other arm of the said lever being connected with a cord 34 trained over pulleys 35 in the base of the case A and connected with treadle 36 fulcrumed at 37 and which, upon rocking, moves the vertical shaft 28 and the bow wheel 29 forwardly so that the latter engages the strings of the violin C and, by reason of its rotation, vibrates said strings to produce a musical sound. To provide for engagement of the bow wheel 29 with the proper strings of the violin C the shaft 21 is made laterally shiftable along with shaft 28 and such shifting is accomplished by lever 38 having 105

110

a bifurcated end 39 which engages shaft 21 between two collars 40, said lever being pivoted at 41 and having its lower end connected with rod 42 which, in turn, connects 5 with lever 43 fulcrumed at 44 on member 45 and having its forward end connected at 46 with the toe piece 47.

Supported in bearings 48 and 49 carried by the U-shaped bracket 50 secured to the 10 base 2, and also in bearings 51 and 52 is a laterally extending shaft 53 carrying a pulley 54 driven from shaft 16 by means of a pulley 55 and belt 56, the pulley 54 being mounted on a sleeve 57 which has key engagement with the shaft and will permit the latter to be laterally shifted for purposes to be hereinafter set forth. Such lateral shifting of the shaft 53 is accomplished by means of the lever 58 pivoted at 59 to a bracket 60 15 carried by the back 2 of the case and guided in the slot 61 cut in the bracket 62. This lever 58 is for engagement by the leg or knee of a person and carries the angular arm 63 pivoted thereto at 64 and provided 20 with a bifurcated end 65 engaging between collars 66 on shaft 53; thus as the lever 58 is shifted to the right or left the shaft 53 will be correspondingly shifted but will still remain in driven relation with respect to 25 the shaft 16. The shaft 53 has loosely mounted thereon the members 67 and 68 in which is journaled a vertical shaft 69 provided at one end with a bevel gear 70 meshing with a bevel gear 71 carried by the shaft 30 53, whereas the other end of the shaft 59 carries the bow wheel 72 similar to the wheel 29 which operates upon the strings of the cello B. It is also necessary, as in the case 35 of the bow wheel 29, to rock the shaft 69 so as to bring the said bow wheel 72 into and out of engagement with the strings of the cello. This is accomplished by loosely 40 mounting the lever 73 on the shaft 69 and providing the same with a peculiarly bent 45 arm 74 one end of which is connected with the lever 73 and the other end of which slides through an eye 75 on a rock lever 76 which may be rocked back and forth by means of the treadle 36 supported at 37 as before 50 stated and having connected therewith the cable 79 also connected with the rock lever 76, said treadle being trained over pulleys 80 and the treadle being retained in its normal position by the spring 81.

55 For fingering the strings on the second violin fingering arms are provided in connection with a bracket 82 in which is mounted a shaft 83 substantially parallel with the neck 84 of the violin C. The shaft 83 accommodates the four fingering arms 85, 86, 60 87 and 87^a the rear ends of which are pressed by means of springs 88 attached at one end to said fingering arm and at the other end to the back 2 of the case A so as to normally 65 maintain the fingering arms in a raised posi-

tion out of engagement with the strings of the violin. The forward ends of the fingering arms 85, 86, 87 and 87^a are provided with pads 89 for engagement with the strings, and it will be understood that each 70 fingering bar is so located as to operate upon a designated string. Immediately adjacent the pad 89 and between the same and the shaft 83, each arm carries an eyelet 90 in which is secured one end of a cord 91 trained 75 over pulleys 92 and through the medium of which the fingering arms are operated by means of the pedals 93. However, the fingering arms are inter-connected by means of shorter flexible members 94 which permit 80 combinations of the fingering arms to be operated.

A similar arrangement operates the fingering arms 95, 96, 97 and 98 of the cello B. These fingering arms are supported on a 85 shaft 99 carried by the bracket 100 and are spring pressed by means of springs 101. However this arrangement differs from that operating upon the strings of the second violin by reason of the fact that each separate 90 fingering arm is connected with cords 102 carried over pulleys 103 and secured at the other end to pedals 104, 105, 106 and 107 respectively.

In order to properly tension the various 95 cords connected with the treadles and pedals, each of these carries a U-shaped member 108 fastened at 109 and carrying the member 110 adapted to wind the cord therein to tighten the same. After tightening the cord, the 100 member 110 is carried by the thumb screw 11 in boss 112.

The operation of the device is as follows:

The operator seats himself before the device with his right foot on the treadle 36 105 and the toe resting in the member 47, then the shank of the operator's limb will be disposed in the member 58. The left foot is used to operate the various treadles 104, 105, 106 and 107 and the two pedals 93. The 110 motor of the device is then started which imparts rotative movement to the two bow wheels 29 and 72. To produce the various musical notes the operator then fingers the strings of the two violins by changing the 115 position of his foot on the treadles and pedals and causes the vibration of the various strings by moving his toe and shank to the right or left to move the bow wheels 29 and 72 and then depresses the treadle 36 120 to cause the bows to contact with the strings. In this way various harmonious combinations of musical notes may be produced; and if the operator so desires he may combine the sounds thus produced with those with 125 which he himself may produce on a violin operated in the usual manner since his hands are left entirely free.

While, in the foregoing I have described one specific embodiment of my invention, it 130

is to be understood that I do not limit myself to such embodiment but may resort to any practical modifications which fall within the scope of the invention as defined in

5 the appended claims.

I claim:—

1. In a device of the class described, the combination with a stringed musical instrument, a power shaft mounted for sliding movement adjacent said instrument, a bracket carried by said shaft, a bow shaft mounted in said bracket, a driving connection between said power and bow shafts, a bow wheel on said bow shaft for engagement 10 with the strings of said instrument, means for sliding said power shaft, and means for moving said bow wheel into and out of engagement with the strings of said instrument.
2. In a device of the class described, the combination with a stringed instrument, of a longitudinally movable power shaft at 15 right angles to the strings of said instrument, a bow shaft driven by said power shaft and disposed adjacent and substantially parallel with said strings, a bow wheel 20
- 25

on said bow shaft, means for moving said bow shaft toward and away from said strings, and means for sliding said power shaft.

30

3. In a device of the class described, the combination with a stringed instrument, of a longitudinally movable power shaft disposed at right angles to the strings of said instrument, a bracket carried by said power shaft, a bow shaft rotatably mounted in said bracket disposed adjacent to and substantially parallel with said strings, a bow wheel on said bow shaft, a power connection between said bow and power shaft, means for 35 moving said power shaft longitudinally, a lever, a connection between said lever and said bracket, the said lever being adapted to move said bracket toward and away from said strings, and a treadle for moving said 40 lever.

In testimony whereof I affix my signature in presence of two witnesses.

CHARLES R. FLEMING.
